Fig. 10

FIG. 1 is a front view of my combined chair, desk and sideboard cabinet, incorporating my invention;

FIG. 2 is a rear view thereof;

FIG. 3 is a top view thereof;

FIG. 4 is a bottom view thereof;

FIG. 5 is a side view looking from the left of FIG. 1;

FIG. 6 is a side view as seen from the right of FIG. 1;

FIG. 7 is a side view thereof as seen from the left side of FIG. 1, but this time with the chair partially swivelled out;

FIG. 8 is a side view thereof as seen from the right side of FIG. 1, but this time showing both the chair and the desk in an inclined position;

FIG. 9 is a perspective view of the combined chair, desk and sideboard cabinet, as seen looking from the front right side thereof; and

FIG. 10 is a perspective view thereof as viewed from the front left side of my combined chair, desk and sideboard cabinet.

I claim:

The ornamental design for a combined chair, desk and sideboard cabinet or similar article, as shown.
